UNITED STATES PATENT OFFICE.

ORESTE G. AGNINI AND RALPH SINGER, OF CHICAGO, ILLINOIS.

BUCKLE.

Application filed February 11, 1928. Serial No. 253,540.

Our invention relates to buckles and pertains more particularly to a two-piece buckle which is readily connected and disconnected, and which when connected gives the appearance of being formed of one piece. The invention is particularly adaptable for use in connection with buckles, the front or face plate portions of which are decorated or mounted with imitation gems such as are generally used on ladies' belts.

An object of the invention is to provide a two-piece buckle of simple construction and without any movable parts, which, when assembled, will simulate a solid or one-piece face plate, and which is so constructed as to be of small dimension in transverse section when assembled so as to lie flat against the dress of the wearer.

Other objects will appear hereinafter.

The invention consists in the combinations and arrangements of parts hereinafter described and claimed.

The invention will be best understood by reference to the accompanying drawings forming a part of this specification, and in which,

Fig. 1 is a front view of an assembled buckle showing a portion of the belt fabric or material at either side; Fig. 2 is a view of the back of the assembled buckle shown in Fig. 1; Fig. 3 is a view of the back of the outer or frame member; Fig. 4 is a view of the back of the interior member, both used in the form shown in Fig. 1; and Fig. 5 is a horizontal sectional view taken on the line 5—5 of Fig. 2.

Fig. 6 is a front view of an assembled buckle of a modified form in which the central portion of the outer or frame member, adapted to receive the inner member, is circular; Fig. 7 is a view of the back of the assembled buckle shown in Fig. 6; Fig. 8 is a view of the back of the inner member; Fig. 9 is a view of the back of the outer or frame member, both of the type used in the form shown in Fig. 6; and Fig. 10 is a horizontal sectional view taken on the line 10—10 of Fig. 7.

Fig. 11 is a front view of an assembled buckle of a further modified form; Fig. 12 is a view of the back of the assembled buckle shown in Fig. 11; Fig. 13 is a view of the back of the inner member; Fig. 14 is a view of the back of the outer or frame member, both used in the form shown in Fig. 11; and Fig. 15

is a horizontal sectional view taken on the line 15—15 of Fig. 12.

Referring to the form shown in Figs. 1 to 5 inclusive, an outer or frame member 18 is provided with a loop 19 for attaching one end of the belt, the inner ends 20 of the wire forming the loop 19 projecting inwardly of the frame 18, for the purpose of retaining the inner member in place as hereinafter explained. Disposed on the inner side of the frame 18, opposite the side having the projections 20, are flanged portions 21. The inner member 22 is also provided with a looped portion 23 to which is attached the other end of the belt. To connect or assemble this form it is but necessary to insert the inner member 22 through the central opening of the outer or frame member 18, after which the back of the member 22 will bear against and be held securely in place by the flanged portions 21 and the projections 20. The belt being preliminarily adjusted to the proper length for the particular wearer, in attaching the belt ends to the loop portions 19 and 23 on the respective parts of the buckle, no manipulation of movable parts is required, and it is but necessary to insert the inner member 22 through the opening in the central portion of the member 18 from the back and in a direction slightly diagonal to the plane of the member 18, a distance sufficient to allow the edge of the member 22 adjacent the loop portion to clear or pass the flange portions 21. Thereupon the respective parts assume the positions shown in Figs. 1, 2 and 5. In order to occupy a minimum of space, the loops 19 and 23 are preferably soldered to the respective buckle parts as at 24.

In the two slightly modified forms shown in Fig. 6 to Fig. 15 inclusive, like reference numerals will indicate like parts in the respective views. In the form shown in Fig. 6 to Fig. 10 inclusive, the inner member 22 (Fig. 8) is provided with a projecting pin 25, which is adapted to be inserted between the two projecting ends 20, 20, upon assembly, in order to prevent any relative displacement of the two parts by reason of the circular shape of the outer member opening and the inner member.

In the form shown in Fig. 11 to Fig. 15 inclusive, because the inner member 22 is comparatively narrow, it is unnecessary to provide retaining flanges or projections on both sides of the central opening in the outer or frame member 18. The flange portion 21 dis-

posed at the side of the opening opposite the loop portion 19, effectually retains the inner member 22 against withdrawal or disconnection when the parts are assembled. It will be seen that the principle of construction and operation are the same as to all of the forms shown.

Upon assembly of the buckle it is unnecessary to provide means for preventing the inner member from being displaced forwardly relative to the outer member, inasmuch as the normal pull exerted by the belt material holds the back of the inner member against the retaining flanges or projections upon the frame member. The thin cross-sectional dimension of the assembled buckle causes it to lie flat against the garment of the wearer, and the assembled buckle has the appearance of being constructed of one piece because of the snug fit between the outer and inner members. Movable parts for attaching the belt to the buckle and for connecting and disconnecting the buckle in use are obviated, and further, the present construction clearly adds to the comfort and convenience of the user.

While we have illustrated and described the preferred forms of construction for carrying our invention into effect, this is capa-

ble of variation and modification without departing from the spirit of the invention. We, therefore do not wish to be limited to the precise details of construction set forth, but desire to avail ourselves of such variations and modifications as come within the scope of the appended claim.

Having described our invention, what we claim as new and desire to secure by Letters Patent is:

A belt buckle of the class described comprising, in combination, a frame member provided with a wire loop for engagement with one end of a belt, said frame member having a central opening adapted to receive an inner member, and an inner member adapted to be inserted and retained in the opening in said frame member and provided with a wire loop for engagement with the opposite end of a belt, the wire forming the belt engaging loop upon said frame member projecting inwardly of said central opening for the purpose of engaging and retaining said inner member in position upon assembling.

In testimony whereof we have signed our names to this specification.

ORESTE G. AGNINI.
RALPH SINGER.
